CLAIM

The ornamental design for a TV tray stand, as shown and described.

DESCRIPTION

FIG. 1 is a perspective view of a TV tray stand showing my new design. The broken lines depicting a typical TV tray are for environmental purposes only and forms no part of the claimed design;

FIG. 2 is a front elevational view of my design, the back elevational view being a mirror image thereof;

FIG. 3 is a bottom plan view thereof;

FIG. 4 is a top plan view thereof; and,

FIG. 5 is a side elevational view of my design, the opposite side being a mirror image thereof.
